CLAIM

The ornamental design for a light equipment for vehicle, as shown and described.

DESCRIPTION

FIG. 1.1 is a front, top, right perspective view of a light equipment for vehicle in an open position, showing the new design, shown as part of the surrounding vehicle wherein the vehicle is not claimed;

FIG. 1.2 is a front elevation view thereof;

FIG. 1.3 is a right side view thereof;

FIG. 1.4 is a front, top, right perspective view of the light equipment for vehicle in a closed position;

FIG. 1.5 is a front elevation view thereof;

FIG. 1.6 is a right side view thereof;

FIG. 2.1 is an enlarged front, top, right perspective view of the light equipment for vehicle shown in FIG. 1.1 showing the new design, without the surrounding unclaimed vehicle;

FIG. 2.2 is an enlarged front elevation view thereof;

FIG. 2.3 is a left side view thereof.

The broken lines of uneven length illustrate the boundary of the claimed design and form no part thereof. The broken lines of even length shown in the drawings illustrate portions of the vehicle that form no part of the claimed design.
